WEB CONTROL FOR CARTON CONVERTING MACHINE

Charles Z. Monroe and Norton G. Raymond, Detroit, Mich., assignors to Ex-Cell-O Corporation, Detroit, Mich., a corporation of Michigan

Original application April 15, 1948, Serial No. 21,296, now Patent No. 2,682,208, dated June 29, 1954. Divided and this application November 16, 1953, Serial No. 392,326

5 Claims. (Cl. 192—127)

The present invention relates to carton converting machines and others of like nature for performing one or more operations on a continuous web of paperboard or the like drawn therethrough. More particularly, the invention relates to the control of the web in such machines.

The instant application is a division of applicants' copending application Serial No. 21,296, filed April 15, 1948 (now Patent No. 2,682,208).

It is the general aim of the invention to provide means for guiding the web as it passes between working parts of a machine of the type described above, and for automatically protecting the machine against bunching of the web or an unduly thick portion therein.

Another object of the invention is to provide a floating shoe riding on the moving web with freedom to be displaced upon the accidental bunching of the web, together with means for stopping the machine upon a predetermined displacement, thereby preventing damage to working parts.

Still another object of the invention is to make possible the accomplishment of the foregoing objectives through the employment of conveniently constructed and organized components which are economical in cost yet reliable in operation.

Further objects and advantages will become apparent as the following detailed description proceeds, taken in connection with the accompanying drawings wherein:

Fig. 1 is a side elevation of an exemplary web scoring and cutting assembly in which the invention is advantageously employed.

Fig. 2 is a fragmentary vertical sectional view taken through the assembly of Fig. 1 and in the plane of the line 2—2, and illustrating one embodiment of the invention.

Fig. 3 is an enlarged fragmentary side elevation of a detector shoe arrangement mounted between the scoring and cutting rolls; the adjustable separating means for such rolls also being indicated.

While the invention is susceptible of various modifications and alternative constructions, a preferred embodiment has been illustrated in the drawings and will be described below in considerable detail. It should be understood, however, that there is no intention to limit the invention to the specific form shown, but on the contrary, the intention is to cover all modifications and alternative constructions falling within the spirit and scope of the invention as expressed in the appended claims.

Inasmuch as the present invention finds especially advantageous, but not exclusive, employment in a carton converting machine of the type described in the aforementioned copending application, reference may be made to Patent No. 2,682,608 for the details of such a machine in order to understand one environment of the invention.

It will suffice here to observe only that the cutting

2

and scoring assembly depicted in Fig. 1 may be a part of a larger over-all machine which performs successive functions on a web W of paperboard or like material drawn continuously from a supply roll (not shown).

5 The machine may include, for example, a printing unit for printing various multi-color indicia on the web W before it reaches the cutting and scoring assembly which scores fold lines in blank and then cuts them around their periphery free of the web. All of the various parts of the machine may be driven in properly timed relation by gearing connection to a main motor (not shown).

As shown in Fig. 1, the scoring and cutting assembly includes a pair of vertically spaced scoring rolls 70, 70A which are fashioned to have a supporting shaft journaled in side frame members. These rolls are adapted to carry mating dies (not illustrated) which embrace the web W as it passes between the rotating rolls, and which thus score or impress fold lines in blanks which are subsequently cut from the web.

15 Spaced from the scoring rolls 70, 70A in the direction of web travel are cooperating upper and lower cutting rolls 71, 71A which may be in general of the same size and shape as the scoring rolls. The cutting rolls 71, 71A are each mounted on a supporting shaft journaled in the side frames of the assembly, and carry sets of mating dies (not illustrated) which bite into the web W as it passes therebetween, partially or completely cutting out the previously scored blanks.

20 For rotating the four rolls 70, 70A, 71, 71A in timed relation to the passage of the web W therebetween, power is transmitted from a main driving motor (not shown) to the scoring and cutting rolls via a countershaft 178 and a connecting gear train (Figs. 1 and 2). As indicated in the drawings, one terminal member of this

25 gear train constitutes a bevel gear 179 which is driven by a meshing bevel pinion 180 fixed to the shaft 178. The other terminal member of the gear train is in this instance a spur pinion 181 which drivingly meshes with gears 182, 184 fixed respectively upon the supporting shafts of the lower scoring and lower cutting rolls 70A, 71A.

30 The gears 182 and 184, in turn, mesh with substantially identical gears 182A, 184A rigidly fixed upon the respective supporting shafts of the upper scoring and upper cutting rolls 70 and 71. To permit a phasing adjustment between the entire scoring and cutting assembly and the remainder of the machine which acts on the web W, a split coupling 186 is made in two angularly adjustable halves 188, 189 which can be clamped relative to each other by means of one or more locking screws 190. The member 188 of the coupling 186 is formed with one or more radial holes for receiving a capstan bar (not shown). To facilitate adjustment of the coupling 186, a flanged hub member 191 is rigidly mounted on the shaft 178 and spaced axially from the coupling 186.

35 Like the member 188, the member 191 also has radial holes for the insertion of a capstan bar. Accordingly, the foregoing adjustment can readily be made by merely loosening the locking screws 190 and rotating the members 188 and 191 with respect to each other by means of a pair of capstan bars.

40 In accordance with the present invention, provision is made for guiding and giving intermediate support to that portion of the web W passing between the scoring rolls 70, 70A and the cutting rolls 71, 71A. As here embodied, there is mounted between these two pairs of rolls a fixed supporting plate 196 (Fig. 3) so arranged that the plane of its upper face generally coincides with a common tangent running between the rolls 70A, 71A.

45 50 55 60 65 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970

of supporting bars 199 which span the web transversely, the shoes 198 being arranged in axially spaced relationship upon such bars (Fig. 2). In the vicinity of each of the shoes 198, the supporting bars 199 are of somewhat enlarged diameter and, in addition, are grooved eccentrically as at 200 in the planes of the respective shoes 198. The eccentric portions 200 of the bars 199 extend through oversize passages 204 defined in the shoes by machined notches 205 and partially covering fingers 206 bolted in place. Since the grooved or eccentric portions 200 are smaller in cross section than the shoe passages 204, each of the shoes has freedom for limited upward floating movement. Furthermore, by simply rotating the bars 199 to various angular positions, the attitude of the shoes 198 and the clearance distance between the shoes and the plate 196 can be readily adjusted. That is, if the two bars 199 are given equal angular adjustment, the shoes 198 will be bodily raised or lowered to increase or decrease the width of the guideway which they define with the plate 196. Adjustment to accommodate webs of different thickness is thus conveniently accomplished. But in addition, if the two bars 199 are given differential angular adjustment, the shoes 198 may be tilted, i. e., changed in attitude, so that the guideway defined with the plate 196 tapers in width, for example, in the direction of web travel, thus smoothing the entry of the web into that guideway.

In order to detect bunching or jamming in the web W as the latter passes across the plate 196 and thus permit appropriate steps to be taken to avoid damaging the machine 50, full advantage is taken of the limited vertical floating movement of which the shoes 198 are capable. Referring more specifically to Figs. 2 and 3 it will be noted that a series of electrical switches 201 is disposed in overlying relationship with the shoes 198. To permit actuation of the switches 201 by respective ones of the shoes, a plurality of vertically movable plungers 202 are interposed respectively between each of the shoes 198 and its associated switch 201. The switches 201 can be arranged to actuate an appropriate stop signal or, alternatively, may be connected directly into the dynamic braking circuit of a main driving motor (not shown) to provide an automatic emergency stop for the entire machine.

For further details of the machine and its operation, reference may be had to the above-mentioned copending application Serial No. 21,296. It is believed that from the foregoing the operation and advantages of the present guiding and protective means will be apparent. However, such operation will be briefly summarized.

As the web W passes through the scoring rolls 70, 70A there may be, under unusual circumstances, a tendency for it to wrap around the upper roll 70, or to sag if the machine has been threaded with slack in the web between the rolls 70, 70A and 71, 71A. The plate 196 positively supports the web to prevent such sagging, while the shoes 198 preclude the web from "wrapping up" on the roll 70. The web is thus guided smoothly from the scoring to the cutting rolls. The manner in which the shoes are mounted on eccentric portions of the rods 199 permits convenient adjustment of the normal height of the shoes above the plate. Simply by rotating the rods 199 this spacing can be adjusted to accommodate webs of varying thicknesses.

Additionally, the floating mount of the shoes 198, permitting them to shift upwardly from their normal position with respect to the rods 199, is combined with the safety switches 201 and means for operating the latter upon a predetermined elevation of the shoes. Thus, should the web tend to bunch or jam between the shoes 198 and the plate 196, the plungers 202 are shoved upwardly to actuate one or more of the switches which may act through a suitable control circuit either to give a warning signal or to quickly stop the machine's driv-

ing motor. Any bunching of the web or unduly thick portion therein is promptly detected by the shoes 198 and switches 201 so that the machine may be stopped before the web is broken and before any damage is done to the dies on either the scoring or the cutting rolls.

We claim:

1. In a machine for converting a moving web of sheet material into carton blanks, said machine having scoring rolls and cutting rolls spaced therefrom longitudinally in the direction of web travel, the combination of a plate interposed between the said scoring and cutting rolls for supporting the web therebetween, guide shoes overlying said plate and spaced therefrom at a distance slightly greater than the thickness of the web, means including an angularly adjustable bar having eccentric portions engaging said shoes for adjusting the position of said shoes above said plate, said means permitting limited vertical floating movement of said shoes, and switch means responsive to the floating movement of said shoes for detecting an abnormal increase in the thickness of the web.

2. In a machine having spaced pairs of rolls between which a continuous web is drawn, the combination of a support plate extending substantially tangentially between the corresponding rolls in each pair and disposed on one side of the web, a cross bar spaced from the opposite side of the web and having a plurality of axial spaced eccentric portions, a plurality of guide shoes having passageways receiving respective ones of said eccentric portions and flat surfaces spaced from the opposite side of the web, means for rotatably positioning said bar to vary the spacing between said shoes and plate to form a guideway for webs of different thicknesses, said passageway being oversize relative to said eccentric portions to permit translation of said shoes away from said plate, a plurality of switches, and means for actuating said switches in response to such translation by respective ones of said shoes, whereby said switches may be employed to stop the machine in the event of the web jamming between said plate and one of said shoes.

3. In a machine for performing operations on a web drawn therethrough, the combination of a support plate over which said web passes, a shoe having two passages therethrough at spaced locations disposed over said web, means for floatably supporting said shoe in vertically adjustable relation above said plate whereby the plate and shoe forms a guideway for webs of different thicknesses, said last named means including two angularly positionable support bars passed through respective ones of said shoe passages and having undersize eccentric portions engaging the shoe passages, equal angular adjustment of said bars thus varying the width of said guideway and differential angular adjustment of said bars changing the attitude of said shoe, and electrical means actuated by upward displacement of said shoe to thereby detect bunching, jamming and thickening of the web between said shoe and plate.

4. In a machine for performing operations on a web and having motive means for drawing the web therethrough, the combination of a support plate, a shoe having a passage therethrough, means for supporting said shoe above said plate at a distance slightly greater than the thickness of the web to thereby define a guide through which the web is passed, said means including an angularly positionable member having an eccentric portion disposed in said shoe passage with freedom for movement relative to the shoe, angular adjustment of said member thereby changing the distance between the plate and the shoe to accommodate webs of different thicknesses while always permitting upward movement of the shoe when the web bunches or jams, and means responsive to such movement by said shoe for stopping said motive means.

5. In a machine for performing operations on a continuous web drawn therethrough and having a pair of

cutting rolls spaced in the direction of web travel from a pair of scoring rolls, the combination of a plate extending substantially tangentially between said rolls to support the web, a shoe having a flat bottom surface and tapered edges overlying said plate and web, said shoe also having a transverse passage, an angularly positionable bar having an eccentric portion loosely disposed in said passage for supporting said shoe adjustably spaced above the web and with freedom to shift upwardly, a switch, and means for actuating said switch upon such shifting of said shoe, whereby said shoe and plate constrain said web to run directly from the scoring rolls to the cutting rolls and said switch is actuated by bunching of the web to elevate said shoe.
